Primary Examiner — Selina Sikder(74) *Attorney, Agent, or Firm* — Faegre Baker Daniel LLP(57) **CLAIM**

The ornamental design for a photoelectronic sensor, as shown and described.

DESCRIPTION

FIG. 1 is a front, top and right side perspective view of a photoelectronic sensor showing my new design;

FIG. 2 is a rear, bottom and left side perspective view thereof;

FIG. 3 is a front view thereof;

FIG. 4 is a top plan view thereof;

FIG. 5 is a bottom plan view thereof;

FIG. 6 is a right side view thereof, the left side view being a mirror image of FIG. 6;

FIG. 7 is a cross-sectional view taken along line 7-7 in FIG. 3; and,

FIG. 8 is a cross-sectional view taken along line 8-8 in FIG. 3. The features shown in broken lines in the drawings depict environmental subject matter only and form no part of the claimed design. The dashed-dotted lines denote the boundary of the claim and form no part of the claimed design.
